UNITED STATES PATENT OFFICE.

RENÉ AUGUSTE BIBARD, OF BELLEVUE, FRANCE.

FLYING APPARATUS.

Application filed July 12, 1924, Serial No. 725,711, and in France July 13, 1923.

This invention relates to improvements in flying machines and especially with reference to the provision of a fork or stirrup to be installed on one end of the fuselage of a 5 flying machine such as an aeroplane and a frame for carrying a machine or other gun and a gunner to operate the same, together with means to enable the gunner to train the gun in any direction whether up or down or 10 laterally as may be required by a target such as an enemy plane or a body of troops, and while the flying machine may be describing any of the evolutions required in battle.

One object of the invention is to provide 15 improved means for inclining the gun carrying frame in a longitudinal vertical plane with respect to the flying machine.

Another object is to provide improved 20 means for inclining the gun carrying frame laterally with respect to the flying machine.

Another object is to effect improvements in the construction of the said frame.

A further object is to provide improved 25 means for protecting the aviator or pilot from the wind.

In the accompanying drawings:

Figure 1 is a longitudinal section and a 30 vertical one passing through the centre of the apparatus.

Figure 2 is a horizontal section passing 35 through the axes of suspension around which the aviator turns, the one of the fork and the one of the frame.

Figure 3 is a vertical and a transverse section passing through the axis of the frame.

The fuselage is here shown as of the usual construction the upper and lower members thereof being indicated at 63, 64. Arranged 40 longitudinally of the fuselage and extending forwardly therefrom is a pivotal shaft 4 which may be tubular and which is mounted in bearings 4^a provided midway between the sides of the fuselage. The rear end 1^a 45 of a fork frame is secured at its center to the front end of said pivoting shaft and said frame has triangular sides 1 truncated at the front end as at 2. These sides extend downwardly as well as forwardly from the 50 pivoting shaft so that the center of gravity of the forked frame is below the shaft as will be noted on reference to Figure 1. In practice the side frames 1 may be covered with sheet steel or other protecting material.

55 A transversely arranged bar 3 extends through and connects the front portions of

the sides 1 of the fork frame and is here shown as provided at one end with a nut 3^a and at the opposite end with a nut 11. Said bar also has an enlarged portion 10 which 60 bears against the inner side of the right hand side of the fork frame 1. On said bar is a spur gear 9 which is secured against rotation by screws 9^a which pass therethrough and through said side of the fork frame and 65 hold said gear against the portion 10. A sleeve 12 is arranged on the bar 3 for turning movement and is provided at the center with a depending arm 14 which has a bearing 15 at its lower end. A tubular bar 23' 70 extends rearwardly from the central portion of the arm 14 a suitable distance, is bent upwardly as at 17' and has an extension 17^a which extends upwardly and is curved rearwardly as shown and forms the support for 75 a correspondingly curved back 18. A bar 25 extends downwardly and rearwardly from the upper portion of the arm 14 and is united at its lower end to said bar 23'. A bar 16 extends upwardly and rearwardly 80 from the lower end of said arm 14 and is united at its upper end to said bar 23'. A vertical tubular bearing 19 is arranged at a suitable distance in front and somewhat higher than the upper end of the arm 14 and 85 is connected to the upper end of said arm by an inclined bar 23 and its lower portion is also connected to the lower end of said arm 14 by an inclined bar 22. A bar 24 connects the bar 22 to the central portion 90 of the arm 14. A seat 17 for the gunner is supported on a bracket 17^b which has a downwardly extending arm 17^c which is mounted in the joint between the members 23', 25, 26, as shown. An arm 26 extends 95 rearwardly from the bar 25, at a suitable point and secured to its rear end is a shield 30 which is arranged at a suitable height to press against the abdomen of the gunner. The upper end of the bearing 19 is connected to the back 18 by rearwardly diverging bars 28. In practice a belt will be worn by the gunner and will be connected by a suitable strap or straps to the bar 23' at the point indicated at 33. A mitrailleuse 21 or 100 other suitable machine gun is provided with a supporting pivot 20 which is mounted in the bearing 19 so that the gun may be either turned on its trunnions as required or moved 105 pivotally in the bearing 19 as may be required in sighting and firing.

110 A pair of vertical arms 5, 13 depends from

and is pivotally mounted near the upper ends on the transverse bar 3 and said bars are provided at their lower ends with bearings 5^a, 13^a respectively which are in line 5 with the bearing 15. A double crank shaft 7 has its central portion mounted in the bearing 15 and its end portions mounted in the bearings 5^a, 13^a. The cranks of this crank shaft are provided with suitable ped- 10 als 7^a for the feet of the gunner and to one end of the crank shaft is secured a spur gear 6 for rotation therewith which spur gear is arranged near the arm 5 and is in vertical alignment with the gear 9. Inter- 15 mediate gears 8 connect the gears 6 and 9 as shown and are mounted on suitable sup- porting axles or studs 8^a. The uppermost gear 8 has an axle shaft 8^b which extends through and has a bearing in the arm 5 and 20 is provided at its inner end with a peripher- ally notched locking disk 31. A locking dog 32 is provided which may be engaged with any of the notches of the disk 31 in order to secure the gun and gunner carrying 25 frame in any desired adjustment in a vertical plane. When the dog 32 is disengaged from the locking disk the gunner by oper- ating the crank shaft and thereby imparting rotation to the train of gears 8 may cause 30 the uppermost of said gears by engagement with the fixed gear 9 to incline the said frame forwardly or rearwardly to any ex- tent to enable the gunner to train the gun and keep the same trained on the target 35 whether that be an enemy plane, a body of troops or other target, and this regardless of the position and plane of movement of the aeroplane on which the said frame and the said fork are installed.

40 I also provide means to tilt or incline the gun carrying frame laterally to any desired extent and with respect to the aeroplane, to compensate for lateral movements or incli- nations of the latter when in flight, which 45 means I will now describe. An aileron or wing 34 of suitable size and shape is ar- ranged at one side of the gun carrying frame and is provided with a shaft or bar 45^a which is arranged in vertical alignment with the 50 pivoting crossbar 3 and is provided at its inner end with a screw-threaded extension 45 which passes freely through openings in the inner and outer ends of a casing 46 which is secured to one side of the gun carrying 55 frame, the said threaded extension passing through and having threaded engagement with a nut element 2^a provided in the side 2 of said frame. A coiled extensile spring 48 is arranged in said casing, the outer end 60 of said spring bearing against the outer end of said casing and the inner end of said spring bearing against a stop 47 with which the threaded extension 45 is provided so 65 that the said spring exerts its tension to move the bar 45^a inwardly and by reason

of the threaded engagement of said bar thus normally maintaining the wing or aileron 34 in a horizontal position so that its front edge offers minimum obstruction or resistance to the air. This initial position of said 70 aileron is maintained while the gun carrying frame is vertical.

A bushing 35 is mounted for sliding move- 75 ment on the hub member 12 and is connected by rods 41, 42 to a disk 43 which has a cen- tral opening through which the pivoting bar 3 extends, said disk bearing against and being revolvably, slidably related to the inner end of the bar 45^a. The hub member 12 is provided on opposite sides with arms 39, 40 80 the latter being provided with ratchet teeth 40^a. A bifurcated lever 38 has the lower ends of its downwardly extending arms piv- 85 otally connected as at 38^a to the arm 39 and also connected pivotally or slidably as at 38 to lugs 37^a which are provided on the front and rear sides of the bushing. Hence said bushing can be operated by the gunner by means of the lever 38 to move the bushing 90 outwardly or inwardly and correspondingly 95 move the disk 43. When said disk is moved outwardly by reason of its revolute and slidable engagement with the inner end 35^a which exerts outward thrust on said bar thus causing said bar by reason of its threaded 100 engagement with the member 2^a to partly turn and to thereby correspondingly turn the aileron 34. The air resistance on said aileron occasioned by the forward motion of the aeroplane causes the gun carrying frame 100 to tilt laterally as will be understood and to an extent corresponding to the adjusted position in which the aileron is placed and held. A suitable locking dog 40^b is provided 105 for engagement with the ratchet teeth 40^a to lock the lever 38 and hence also the aileron 34 in any desired adjusted position.

To shelter the aviator from the wind I provide a pair of panels 52, 53 which panels are respectively hinged at their rear edges 110 to the upper and lower sides of the fuselage and are connected together by a bar 56 and rings 54, 55, which rings are pivotally connected to the said panels and also to the ends of said bar. The bar 56 has a rearwardly 115 extending centrally located guidebar 56^a which is slidably mounted in an opening in a crossbar 58 of the fuselage and is provided at its rear end with a stop 56^b. A coiled extensile spring 57 is arranged on said 120 guidebar, bears between the stop 56^b and the cross-beam 58 and normally holds the bar 56 at the rearward limit of its movement so that the panels will be held thereby in hori- 125 zontal, closed position. To enable the avia- tor to readily operate the bar 56 and cause the panels to open to the position shown in Figure 1 I provide a suitable strip or cord 59 which is attached to the central portion of said bar 56 extends forwardly under a 130

5 pulley 59^a and under a pulley 59^b, which pulleys are mounted as shown, the said cord extending forwardly and being secured in any desired adjusted position to a suitable cleat 60. By pulling forwardly on the cord the aviator may cause the bar 56 to move forwardly to open the panels or wind screens to any desired extent.

10 The fork and the frame and the means for operating them may be employed for commercial purposes as well as for military purposes.

15 In the drawing I show a pair of crutches 61, 62 at opposite sides of the bottom of the fuselage, at the front end thereof, which crutches are of leaf spring construction.

Operation of the device.

20 In the moment of fighting the gunner holding in his left hand the handle controlling the motions of the fork around the longitudinal axis, directing with his pedals the movement of the frame around the transverse axis, regulates at the same time the inclination of his seat and that of the weapon, that is to say, he is placed in face of the latter in the same relative position, with the same facilities for aiming and firing. By his right hand he regulates the proper motions 25 of the gun which add themselves to those of the fork and of the frame and increase the rapidity of gaging.

30 *Advantages and utilization.*—The possibility of turning in a vertical and longitudinal circle assures to the gunner the sole means of fighting with advantage against aggression most to be feared; the one where the aggressor describes one-fourth of a circumference behind and below the machine. 35 The gunner in the tower heretofore used perceives the same only at its most rapid falling speed and then he finds himself suddenly without defense; exposed to strokes of an enemy who is invisible at the moment 40 when he is nearest. The gunner in the fork, however, does not lose for a moment the view of his adversary and is facing the same constantly. Hence he is in a better condition 45 for firing than the enemy. He pursues him below the machine or above the same up to the limit of reach of his weapon, if he so desires. The machine with a fork appears practically unapproachable for near 50 fight. Since the apparatus is more stable, owing to its construction, and its lifting or carrying power is very high, this invention makes it possible to arm an aeroplane with

a gun of small calibre mounted and arranged for firing at long distance, and to dispense definitely with the light machine 60 advantageous only for rapid exploration.

Having thus described my invention, what I claim is:

1. In combination with a flying machine, a fork mounted thereon for rotation about a 65 longitudinal axis and a frame mounted for turning movement about a fixed axis extending transversely of the prongs of the fork, said frame being arranged to carry a weapon and being provided with a seat for 70 a gunner.

2. In combination with a flying machine, a fork mounted thereon for rotation about a longitudinal axis and a frame mounted for turning movement about a fixed axis extending 75 transversely of the prongs of the fork, said frame being arranged to carry a weapon and being provided with a seat for a gunner and means including a foot lever to control the turning movement of the 80 frame.

3. In combination with a flying machine, a fork mounted thereon for rotation about a longitudinal axis and a frame mounted for turning movement about a fixed axis extending 85 transversely of the prongs of the fork, said frame being arranged to carry a weapon and being provided with a seat for a gunner and means including foot levers and a transmission train of epicycloidal 90 gears to control the rotation of said frame.

4. In combination with a flying machine, a fork mounted thereon for rotation about a longitudinal axis and a frame mounted for turning movement about a fixed axis extending 95 transversely of the prongs of the fork, said frame being arranged to carry a weapon and being provided with a seat for a gunner and means to control the turning movement of the fork and including a crank 100 fixed on the frame.

5. In combination with a flying machine a fork mounted thereon for lateral inclination with respect thereto and arranged to maintain itself by gravity in a normal vertical plane, a frame mounted on said fork for longitudinal vertical inclination with respect to the machine, means to cause said fork to be laterally inclined with respect to said machine, said means including an 105 aileron, and means to operate the aileron.

In witness whereof I affix my signature.

RENÉ AUGUSTE BIBARD.
